COMBINED HIGH CHAIR AND YOUTH CHAIR

Arnold E. Peterson, Glendale, Calif.

Application February 14, 1957, Serial No. 44,865

Term of patent 14 years

(Cl. D15—1)

Fig. 1 is a perspective view of a chair showing my new design; and

Fig. 2 is a front perspective view of the chair as it appears when used as a youth chair.

I claim:

The ornamental design for a combined high chair and youth chair, substantially as shown.
